UNITED STATES PATENT OFFICE.

SAMUEL P. GLUNT, OF UNION CITY, INDIANA.

SLATE-CUTTER.

SPECIFICATION forming part of Letters Patent No. 552,364, dated December 31, 1895.

Application filed May 15, 1895. Serial No. 549,437. (No model.)

To all whom it may concern:

Be it known that I, SAMUEL P. GLUNT, of Union City, in the county of Randolph and State of Indiana, have invented a new and Improved Slate-Cutter, of which the following is a full, clear, and exact description.

The object of the invention is to provide a new and improved slate-cutter which is simple and durable in construction and designed for the use of slaters, to enable the latter to properly, conveniently and quickly trim the slate as required, and to provide the same with nail-holes previous to placing the slate on the roof.

15 The invention consists principally of a knife adapted to swing, and formed with two parallel cutting-edges separated by a longitudinal groove.

The invention also consists of certain parts 20 and details and combinations of the same, as will be fully described hereinafter and then pointed out in the claim.

Reference is to be had to the accompanying drawings, forming a part of this specification, 25 in which similar characters of reference indicate corresponding parts in all the figures.

Figure 1 is a perspective view of the improvement. Fig. 2 is a transverse section of the same on the line 2 2 of Fig. 3. Fig. 3 is 30 a longitudinal sectional side elevation of the improvement. Fig. 4 is a sectional side elevation of a modified form of connection between the knife and operating-lever, and Fig. 5 is a plan view of the same.

35 The improved slate-cutter consists of a frame A provided with two longitudinally-extending bars A' and A², held a suitable distance apart, and formed at their ends with legs A³ and A⁴, preferably made in the shape 40 of points, so as to conveniently attach the frame to a board, block or like device by driving the points into the wood. The two longitudinal bars A' and A² support a transversely-extending pivot B, on which is pivoted the cutter C, formed with two cutting-edges C' parallel to one another and separated by a V-shaped groove, as is plainly illustrated in Fig. 2. The rear end of the cutter C carries a pivot D passing through an 45 elongated slot E' in a lever E fulcrumed at D' on the bars A' and A², and adapted to im-

part a swinging motion to the latter. The lever E is formed at its outer end with a handle E² adapted to be taken hold of by the operator to impart a swinging motion to the 55 said cutter, to cause the cutter C to cut the slate placed on the bars A' and A² in front of the cutter, as indicated in Fig. 1.

On the handled end E² of the lever E is arranged a pin F, operating over an aperture 60 A⁵ in the leg A³, to enable the operator to punch holes into the slate by placing the latter over the aperture A⁵, and then bringing the lever E down, so as to force the pin or punch F through the slate. The connection 65 between the lever E and cutter C may be made in various forms—for instance, as shown in Figs. 4 and 5, in which the pivoted cutter C² is provided on its pivot end with gear-teeth C³ in mesh with corresponding teeth E⁴, secured on the forward end of the lever E⁵. Now when the latter is moved upward, a like upward swinging motion is given to the cutter C², and when the lever is brought down the cutter C² swings downward to trim the slate, 75 as previously mentioned.

It will be seen that this device is very simple and durable in construction, and by the use of the double cutting-edges of the cutter the cut particles of slate give away readily, 80 so that a straight edge may be cut on each part of the slate.

The cutter C is preferably made in two parts, as indicated in the drawings, to admit of the parts being turned on the pivot, to allow them to be easily sharpened whenever necessary.

In order to limit the downward-swinging motion of the lever E when punching holes in the slate by the pin or punch F, I provide 90 a stop G, connecting the two bars A' and A² with each other, the said stop being engaged by a recess E⁶ formed in the lever, as is plainly shown in Fig. 3. The slot E' permits the lever and knife to be turned from a straight line 95 in raising the lever-handle during the cutting and punching operation.

Having thus described my invention, I claim as new and desire to secure by Letters Patent—

100 In a slate cutter, the combination with a frame composed of two bars having parallel

portions spaced apart and having their extremities bent downwardly and formed with points, of a knife pivoted between the bars and having its cutting edge capable of moving past the same, and a lever fulcrumed between the bars and pivotally connected to the knife, the lever having at the end opposite

the knife a downwardly projecting pin or punch, substantially as described.

SAMUEL P. GLUNT.
